UNITED STATES PATENT OFFICE.

JACOB ZIEGLER, OF COFFEYVILLE, KANSAS.

DESIGN FOR A NECK-YOKE CENTER.

SPECIFICATION forming part of Design No. 30,271, dated February 28, 1899.

Application filed January 30, 1899. Serial No. 703,910. Term of patent 14 years.

To all whom it may concern:

Be it known that I, JACOB ZIEGLER, a citizen of the United States, residing at Coffeyville, in the county of Montgomery and State of 5 Kansas, have invented and produced a new and original Design for a Neck-Yoke Center, of which the following is a specification.

This invention relates to a new and original design for a neck-yoke center; and it has 10 for its object to provide a design of this character that shall be both useful and ornamental.

The leading feature of the design resides in 15 a neck-yoke loop provided with a pair of spaced pole-rings depending from its lower side and arranged in parallel relation, said rings being of different diameters and eccentrically disposed with their lower sides intersected by a common plane.

20 Another feature of the design resides in the pair of pole-rings being obliquely disposed to the transverse center of the neck-yoke loop and oppositely-located approximately horizontal L-shaped braces connecting contiguous side portions of the two rings.

The minor features of the design are the 25 neck-yoke loop, being of an oval shape, the larger pole-ring having a round rim portion and the smaller pole-ring having a wide flat 30 rim portion and provided at its top with a narrowed web or neck joined to the neck-yoke loop contiguous to one end of the latter.

In the drawings, Figure 1 is a perspective 35 view of a neck-yoke center embodying the herein-described design. Fig. 2 is a side view thereof. Fig. 3 is a vertical section view of the same. Fig. 4 is an end view. Fig. 5 is a top plan view.

40 Referring to the accompanying drawings, the numeral 1 designates the neck-yoke loop,

which is of an approximately oval shape and is provided at its upper and lower sides with vertically-alined bearing-openings 2. The said oval neck-yoke loop is also provided with a pair of spaced pole-rings 3 and 4, respectively, depending from its lower side, the pole-ring 3 being joined to the loop at a point centrally between the ends of the latter and the other pole-ring 4 being joined to the loop contiguous to one end of the same, as plainly 45 shown in Fig. 2 of the drawings. The pair of spaced pole-rings 3 and 4, depending from the lower side of the loop 1, are arranged in parallel relation, and are also disposed obliquely to the transverse center of the neck-yoke loop 1. The said rings 3 and 4 are of 50 different diameters and are eccentrically disposed with their lower sides intersected by a common plane. The larger pole-ring 3 is provided with a rounded rim portion, while the 55 smaller pole-ring 4 is provided with a wide flat rim and at its upper side with the narrowed web or neck extension 5, joined to the body portion of the neck-yoke loop 1. The smaller pole-ring 4 is provided with an interior cylindrical sleeve portion 6, and to complete the design the contiguous side edge portions of the two rings 3 and 4 are connected by the oppositely-located approximately horizontal L-shaped braces 7. 60

70 What is claimed is—

The design for a neck-yoke center, herein shown and described.

In testimony that I claim the foregoing as my own I have hereto affixed my signature in 75 the presence of two witnesses.

JACOB ZIEGLER.
